CARBURETOR STRUCTURE

August H. Blattner, Pine Lawn, and Fred A. Kommer, St. Louis, Mo., assignors to Carter Carburetor Corporation, St. Louis, Mo., a corporation of Delaware

Application July 2, 1936, Serial No. 88,566

3 Claims. (Cl. 261—52)

This invention relates to carburetors for internal combustion engines and consists particularly in novel inter-connection control means between the choke and throttle valves.

- 5 A copending application Serial No. 666,118, filed April 14, 1933, in the names of George M. Bicknell and Otto Henning, and copending applications Serial No. 83,066, filed June 2, 1936, and Serial No. 89,088, filed July 6, 1936, both in 10 the name of August H. Blattner, illustrate carburetor choke and throttle valve interconnection mechanisms arranged to limit closing movements of the throttle valve to the fast-idle position when the choke is closed and to force the choke valve 15 substantially open when the throttle valve is open. The last two mentioned applications also illustrate means for locking the choke valve when both the choke and throttle valves are fully open.

The present invention comprises a novel choke 20 and throttle valve interconnection mechanism embodying fast idle, unloading, and choke lock features somewhat as in the above-mentioned applications, the mechanism being adapted to be applied to an automatic choke carburetor having 25 the choke control mounted on the air horn and on the same side of the carburetor as the interconnection. The present construction embodies certain structural and functional differences and advantages over the corresponding 30 mechanisms of said applications.

One object of the present invention is to provide novel choke and throttle valve interconnection mechanism in which the principal parts thereof are compactly located near the lower portion 35 of the carburetor.

Another object is to provide choke and throttle valve interconnection mechanism for a carburetor in which the interconnection and the automatic choke control are located on the same side.

40 In the accompanying drawings:

Figure 1 is a side view of a carburetor embodying the invention, portions being broken away and sectioned for clearer illustration.

45 Figures 2, 3, and 4 are diagrammatic views of the choke and throttle valves and interconnection mechanism in different operative positions.

The carburetor in Figure 1 is of a well known downdraft type, including a mixture passage having an air inlet horn 1, mixing chamber 2, venturis 3, and a flanged outlet portion 4 for attachment to the intake manifold (not shown) of an associated engine. Pivoted in the air horn on shaft 5 is an unbalanced butterfly type choke valve 6, and throttle valve 7 is pivoted on shaft 8 50 in the lower portion of the mixture passage. The

choke valve is provided with an automatic control mechanism, including a thermostat 30, in a housing 31 mounted adjacent the air horn. A choke control of this type is more fully disclosed in Coffey patent No. 2,085,351. Adjacent the 5 mixture passage is a bowl 9 within liquid fuel is maintained at a substantially constant level by a float 10. Fuel from bowl 9 passes through metering jet 11 into main nozzle 12, discharging into the throat of the smaller venturi 3, and an 10 idling passage, part of which is shown at 13.

Pivoted on member 14 adjacent the throttle shaft 8 is a cam-like member, generally indicated at 15, and having a laterally projecting pin 16 received in slot 17 in the lower portion 15 of link 18. Link 18 is pivoted at its upper end to crank 19 rigid with the choke valve shaft 5. In the present instance, choke shaft 5 extends outwardly beyond the crank 19 for attachment of automatic choke control means (not shown) on 20 the same side of the carburetor as the interconnection mechanism.

Throttle control crank 20 is constructed as at 21 for manual operation and has an adjusting screw 22 for cooperation with cam-like member 15, when the choke valve is closed, to prevent full closing of the throttle valve. Projecting from crank 20 is a foot-like portion 23 having a toe 24 and a heel 25. Cam-like member 15 has a lateral pin 26 for cooperating with heel 25 to 30 manually open the choke valve, and link 18 has a lateral offset 27 at its lower extremity for cooperating with toe 24 to lock the choke valve when both the throttle and choke are substantially fully open.

35 The operation of the interconnection mechanism is substantially as follows:

Figure 4 shows the valves in the fast idle position with the choke valve held closed by the thermostat and the throttle valve partly opened, 40 the position of the throttle being substantially exaggerated for clearness. Preferably the throttle will be opened beyond the fast idle position for cold starting. During cranking, and after the engine starts to run, choke valve 6 may open to the extent indicated by the broken line position (Figure 4), due to the slot and pin connection between cam-like member 15 and link 18, without necessarily affecting the position of the cam-like member. Also the throttle valve 45 may be fluctuated, in order to prime the engine by means of the accelerating pump, without affecting the choke valve. As long as the choke valve remains in a substantially closed position, high point 15a on the cam-like member will be 50 55

positioned to be engaged by screw 22, to limit the closing movement of the throttle to the fast idle position. During opening of the choke valve, the cam-like member rotates counterclockwise under the influence of weighted lobe 15d thereof, and other points 15b on the cam-like member at progressively decreasing distances from the axis thereof will be moved opposite throttle abutment screw 22, whereby the throttle may assume intermediate fast-idle positions, approaching closer and closer to its fully closed position as the choke valve opens.

In case of overenrichment of the mixture during cranking, which may be due, for instance, to excessive fuel charges from the accelerating pump or to sticking of the choke valve, the intake system may be "unloaded" by opening of the throttle valve, as shown in Figure 2, to the point where heel element 25 engages pin 26 to rotate cam-like member 15 counterclockwise and open the choke valve. The ensuing gust of air through the carburetor and intake manifold serves to clean out excess fuel therein.

When the throttle valve has been fully opened, the choke valve is free to open farther, as shown in Figure 3, under the influence of the automatic choke control mechanism. When the choke has fully opened, lip 27 will lie beneath toe element 24 on the throttle crank so as to prevent closing movement of the choke valve as long as the throttle remains fully open. The lower portion of slot 17 is slightly enlarged to permit lip 27 to pass toe 24 and drop beneath the same by gravity. If desired this action may be made more certain by a spring. The choke open lock feature is particularly useful in connection with though not limited in use to an automatic choke control as shown in copending application of I. E. Coffey, Serial No. 679,201, filed July 6, 1933, in which warm air is drawn past the choke control thermostat by a suction by-pass from the intake manifold. With such arrangement, in case the intake suction drops for a substantial period after the choke is open, due, for instance, to acceleration or low speed operation with the throttle open, the thermostat may cool sufficiently to partly close the choke, resulting in excessive richness of the mixture. The choke open lock permits restricting the heat applied to the thermostat when the choke is wide open to prevent excessive heating of the thermostat and also stabilizes the choke valve under normal operating conditions.

After the choke valve has opened fully, the throttle valve is free to move within its full range of operation without being affected by the interconnection mechanism. Figure 1 illustrates the throttle valve fully closed to its normal idle position with screw 22 opposing low point 15c on the cam-like member.

The novel interconnection mechanism described is of compact, rugged, and simple construction, and functions effectively to insure the desired interrelated choke and throttle movements and positioning of the choke and throttle

valves. The principal portions of the mechanism are located adjacent the lower part of the carburetor so as not to interfere with or be obstructed by the automatic choke control mechanism which, in the present instance, is mounted on the same side of the carburetor as the interconnection mechanism.

Obviously, the invention is not limited in details to the structure shown, but may be modified in various respects as would occur to those skilled in the art, and the exclusive use of all such modifications as come within the scope of the appended claims is contemplated.

We claim:

1. In a carburetor, choke and throttle valves, a thermostatic control for said choke valve, members movable with said valves, a part pivoted adjacent the member movable with said throttle valve, said last-mentioned member having an abutment, and a link connecting said part and the member movable with said choke valve and having a projection disposed to underlie said abutment only when both of said valves are substantially fully open to prevent closing of said choke valve independently of said throttle valve. 25

2. In a carburetor, choke and throttle valves having pivotal shafts, a thermostatic control for said choke valve, arms on said shafts, a cam-like member pivoted to the carburetor immediately adjacent said throttle shaft, and a link member connecting said cam-like member and said choke arm, one of said members having a pintle thereon and the other having a slot receiving said pintle whereby said link member is permitted substantial longitudinal lost motion relative to said cam-like member, said cam-like member having a plurality of portions at different distances from the pivotal center thereof, and the arm on said throttle valve shaft having an abutment for selectively engaging said portions when said choke valve is not fully open to variably prevent full closing of said throttle valve, said throttle arm and said cam-like member having other abutments cooperating when said throttle is substantially opened, to take up the lost motion between said link member and said cam-like member and open said choke valve and also cooperating when both of said valves are substantially fully open to lock said choke valve. 40 50

3. In a carburetor, choke and throttle valves, a thermostatic control for said choke valve, members movable with said valves, a part pivoted adjacent the member movable with one of said valves, said last-mentioned member having an abutment, and a link connecting said part and the member movable with the other of said valves, and having a projection disposed to underlie said abutment only when both of said valves are substantially fully open to prevent closing of said choke valve independently of said throttle valve. 55 60
